[57] **CLAIM**

The ornamental design for a garment bag, substantially as shown and described.

DESCRIPTION

FIG. 1 is a front elevational view of a garment bag showing my new design;

FIG. 2 is a right side elevational view thereof;

FIG. 3 is a rear elevational view thereof;

FIG. 4 is a bottom plan view thereof;

FIG. 5 is a top plan view thereof;

FIG. 6 is a perspective view of the garment bag in folded position;

FIG. 7 is a rear elevational view showing the opposite side from that illustrated in FIG. 6 thereof;

FIG. 8 is an unfolded side elevational view showing the side opposite that illustrated in FIG. 2;

FIG. 9 is a side elevational view of the garment bag in folded condition;

FIG. 10 is a top plan view of the garment bag in folded position; and,

FIG. 11 is a bottom plan view of the garment bag in folded position.

FIG. 1

FIG. 2

FIG. 3
